UNITED STATES PATENT OFFICE

CALEB B. HEINSMAN, OF PEORIA, ILLINOIS

VALVE

Application filed April 9, 1930. Serial No. 442,924.

This invention relates to improvements in fire extinguishing apparatus and more particularly to a novel means for effecting automatic delivery of water under pressure to spray nozzles when the nozzles are subjected to heat from a fire in the vicinity thereof, the nozzles being of that type in which the fusing of an element thereof will effect automatic opening of the nozzle and one of the objects of 5 the present invention is to provide, in a control means for the purpose stated a novel combination and arrangement of valves by which water will not be present in the water conducting pipe or pipes with which the spray nozzles 10 are associated, under normal conditions, so as to provide for a more certain fusing of the elements of the spray nozzles, referred to above, than would be practicable than if the said pipe and these nozzles were filled with 15 water.

Another object of the invention is to provide an automatic control mechanism in which the component parts are so constructed and arranged that there will be no liability of 20 displacement of any of the parts and also the invention contemplates a control which will be certain in its action.

This invention also consists in certain other features of construction and in the combination and arrangement of the several parts, to be hereinafter fully described, illustrated in the accompanying drawings, and specifically pointed out in the appended claim, it being understood of course that minor changes may 25 be made so long as they fall within the scope of the claim.

In describing my invention in detail, reference will be had to the accompanying drawings, wherein like characters denote like or corresponding parts throughout the several views, and in which:—

Figure 1 is a vertical sectional view through the control apparatus embodying the invention, both valves of the apparatus being closed and the component parts of the apparatus being therefore in their normal positions.

Figure 2 is a similar view but illustrating the valves in the open position which they will assume in the event of fusing of any of the spray nozzles.

Figure 3 is a horizontal sectional view taken substantially on the line 3—3 of Figure 1, looking in the direction indicated by the arrows.

Figure 4 is a horizontal sectional view on the line 4—4 of Figure 2 looking in the direction indicated by the arrows.

Figure 5 is a detail view illustrating the sprinkler head.

The apparatus embodying the invention 60 comprises a hollow, cylindrical casing indicated by the numeral 1 and provided, preferably, with a removable top indicated by the numeral 2 and a preferably integral bottom indicated by the numeral 3. A water supply pipe 4 is provided at the closed bottom 3 of the casing and is supplied with water from a main, the water being of course under pressure. In the operation of the apparatus, water is delivered to the sprinkler main, which is indicated by the numeral 5, and the intake end of this main is threaded into a nipple 6 formed centrally of the top 2 of the casing, sprinkler heads 7 being arranged at suitable intervals in the length of the sprinkler pipe 5 and this pipe being led in any desired direction and of any desired length and the sprinkler heads being spaced as may be found most desirable in the length thereof. As these sprinkler heads are of a well known 65 type in which the fusing of an element thereof serves to automatically permit opening of the valve of the head for the passage of water from the head, any further description of the same is thought to be unnecessary. 70

In order to normally prevent supply of water from the casing 1 to the sprinkler pipe 5, a novel valve arrangement is installed in the casing 1 and will now be described. Preferably a valve seat 8 is provided at the point of communication of the water supply pipe 4 with the casing and a valve 9 normally rests upon this seat, the valve having a tubular stem 10 which fits slidably through an opening 11 in a spider 12 located within the pipe 4. 75

A head 13 is provided upon the lower end of the stem 10 and, by engagement against the spider, as shown in Figure 2, is adapted to limit the upward movement of the valve 9. As water under pressure is, as before stated, 80

supplied through the pipe 4, the tendency will be for the valve 9 to move to open position, but this is avoided by the employment of a second valve unit which comprises an annular valve seat 14 which is of a diameter to fit within the cylindrical casing 1 and is provided in its periphery with a circumscribing groove 15 in which a packing ring 16, preferably of rubber is seated, so as to contact with the casing wall to prevent the flow of water past the valve seat when the valve which is associated with the seat is in closed position. The valve seat 4 is supported by arms 17 which are arranged in upwardly diverging relation to one another and formed or secured at their lower ends to the upper side of the valve head 9, and at their upper end to the under side of the seat 14. The valve which, as stated above, is associated with the valve seat, is indicated by the numeral 18 and is provided with a stem 19 which projects both above and below the valve and, preferably, the lower end of the stem is of a diameter to fit slidably in the hollow valve stem 10 and its portion which extends above the valve 18 fits slidably through an opening 30 formed in the hub of a spider 21, the arms of which radiate from the said head 20 and are united at their lower and outer ends to the valve seat 14 near the periphery thereof and in sufficiently spaced relation with respect to the upper side of the valve seat to permit of movement of the valve to the open position shown in Figure 2, these arms 21 being arranged in downwardly diverging relation to one another.

Inasmuch as the spray heads or sprinkler heads 7 embody valves which are normally closed, air under considerable pressure may be delivered into the casing 1 by way of a compressed air supply pipe 22 by opening a valve 23 which is interposed in this pipe and it will be observed by reference to Figure 1 of the drawing that the pipe 22 communicates with the casing above the valve 18 and therefore, the valve normally assuming a lowered or closed position, the compressed air will be trapped in the casing above the valve. The pressure of air against the valve, in a downward direction, exerts pressure against the valve seat 14, and as this seat is connected with the valve 9, it will be evident that the valve 9 will be securely held in the closed position. In the event of the outbreak of a fire in proximity to any of the sprinkler heads 7 and the fusing of the thermostatic element of the head, air will first escape through the head, and, due to the reduction of pressure in the casing 1 above the valve 18 and the pressure exerted in an upward direction against the valve 9 by the water under pressure in the valve 4, the valve 9 will be opened and as it opens, it will move the valve seat 14 upwardly in the casing and,

as the air at all times, within the casing above the valve 18 and in the pipe 5, is at substantially atmospheric pressure, the valve 18 will of course be elevated to open position due to the inrush of the water under pressure against the valve 9 and the water will then pass through the pipe 5 and be delivered in a spray through such of the sprinkler heads as have their thermostatic elements fused, and this spray will be continuous so long as water under pressure is supplied through the pipe 4.

Means will of course be provided whereby the supply of water under pressure to the pipe 4 may be cut off but as this does not constitute a part of the present invention no such means has been specifically illustrated in the drawings. It will be evident however, that, due to the provision of a drain opening in the wall of the casing 1, which opening is indicated by the numeral 24, water may be drained from the upper portion of the casing, or in other words, from the space above the valve 18 by removing a plug 25 which normally closed the drain opening. In order that the condition of the parts as well as the water level in the lower portion of the casing may be observed from time to time, the casing is provided with upper and lower hollow bosses 26 each having an opening 27 in its outer side closed by a removable plug 28 and by removing either of these plugs, the corresponding portion of the interior of the casing may be inspected. The opening 27 in the upper boss likewise permits of the insertion of a tool or rod through this opening in order to dislodge the valve seat 14 or valve 18 in the event these parts may not have fully lowered upon the continuation of the supply of water under pressure.

What I claim is:—

In an automatic control for a fire extinguishing system of the class described, a casing having an inlet in its top for the admission of air under pressure, and an inlet in its bottom for the admission of water under pressure, a valve within the casing normally closing the water inlet, a valve seat fitting slidably in the casing, means connecting the said seat with the said valve, means for limiting the movement of said valve and seat, a second valve resting upon the valve seat and movable with relation thereto and normally dividing the casing into chambers to be filled one with compressed air and the other with water under pressure, a tubular stem extending upwardly from the first mentioned valve, and a stem mounted on said second mentioned valve and including a portion extending below and above the second mentioned valve, the lower portion of the last mentioned stem fitting slidably in the tubular stem of the first mentioned valve, a guiding head supported by the valve seat in elevated position above the second mentioned

valve, the upward extension of the second mentioned stem portion extending slidably through and guided by said guiding head, and an outlet leading from the top of the 5 casing for connection with a sprinkler system of the type to be rendered active upon fusing of an element thereof, whereby, upon opening of the system, release of pressure in the upper chamber will permit opening of 10 both of said valves to provide for flow of water to the sprinkler system.

In testimony whereof I affix my signature.
CALEB B. HEINSMAN.
